UNITED STATES PATENT OFFICE.

JOHN S. HAINES, OF DOWAGIAC, MICHIGAN.

SILO.

1,267,863.

Specification of Letters Patent. Patented May 28, 1918.

Application filed March 13, 1916. Serial No. 83,839.

To all whom it may concern:

Be it known that I, JOHN S. HAINES, a citizen of the United States, residing at Dowagiac, county of Cass, State of Michigan, have invented certain new and useful Improvements in Silos, of which the following is a specification.

This invention relates to improvements in silos.

10 The main objects of this invention are:

First, to provide in a silo an improved wall structure.

Second, to provide in a silo an improved door casing structure.

15 Third, to provide in a silo an improved chute structure.

Further objects, and objects relating to structural details will definitely appear from the detailed description to follow.

20 I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

25 Figure I is a detail front view of a structure embodying the features of my invention, with portions of the chute and portions of the hoops broken away to better disclose the structural details.

30 Fig. II is a detail perspective view showing one of the door casing blocks and the relation of the cross bars thereto.

35 Fig. III is an enlarged detail horizontal section on a line corresponding to line 3—3 of Fig. I, showing the details of the door casing structure and of the chute.

40 Fig. IV is an enlarged detail vertical section on a line corresponding to line 4—4 of Fig. III.

Fig. V is a detail section on a line corresponding to line 5—5 of Fig. III.

45 Fig. VI is a detail horizontal section on a line corresponding to line 6—6 of Fig. I.

Fig. VII is a diagrammatic view showing the relation of the wall blocks in the tiers and of the blocks of adjacent tiers, the tiers being shown slightly separated for clearness of illustration.

Fig. VIII is a detail section on a line corresponding to line 8—8 of Fig. I.

In the drawing similar reference characters refer to similar parts throughout the

several views, and the sectional views are taken looking in the direction of the little arrows at the ends of the section lines.

Referring to the drawing, 1 represents the foundation of the silo, which is ordinarily of concrete. The wall blocks 2 and 3 are formed as rights and lefts with rabbet-like recesses 4 at one end extending one-half the width of the blocks. These blocks are laid in pairs with their recesses opposed, 60 that is, rights and lefts are laid so that their recesses register. The blocks are laid in the wall in tiers. The block 2, that is, one block of each pair is longer than the other. The length of the blocks 2 exceeds that of the 70 blocks 3 by the depth of the recesses 4. The blocks of adjacent tiers are lapped one-half their width so that the longer blocks of one tier interlock with the recesses of the blocks of the adjacent tier.

75 The hoops 5, which are preferably in the form of flat bands, are applied so as to engage the blocks at their tier joints. By this arrangement of interlocking joints the hoops effectively engage the blocks of both 80 tiers. If desired, the blocks may be provided with tongues and grooves on their edges, but, as such expedients are well understood, I have not illustrated the same herein.

85 The door casing blocks 6 are laid in the wall with the wall blocks, the casing blocks, however, vary in width in order to complement the wall blocks of the tiers.

The door casing blocks are provided with 90 face plates 7 of metal. The face plates have arm-like lugs 8 struck in therefrom and embedded in the blocks. The door casing blocks have recesses 9 at their ends, while the facing plates have slots 10 registering 95 with these recesses. The recesses and slots of adjacent blocks register when in position in the wall, providing mortises for the tenons 11 of the cross bars 12. These cross bars are arranged with their ends abutting 100 the face plates of adjacent blocks and their tenons projecting into the mortises or recesses provided therefor.

The doors are beveled at their vertical edges, as 14, to fit against the inclined shoulders 15 on the casing blocks. The casing blocks are thickened at 16 to provide these shoulders and to strengthen the blocks. The doors are clamped in position one above the other by means of bolts 17 and retaining 110

bars 18, the bars being arranged to engage the casing blocks and clamped in place by the bolts.

I preferably provide a chute consisting of 5 sections 20 formed of sheet metal and provided with edge bars or uprights 21 at their edges. These uprights are preferably strips of angle iron disposed with their angles facing inwardly. These angle bars have 10 notches or slots 22 at their ends adapted to engage the hoops 5 so that the chute sections are effectively supported. The sections are preferably arranged with their ends overlapped, as shown in Fig. VIII. By this arrangement the chute is very economical in 15 its parts and the parts are conveniently and quickly assembled in the erection of the silo.

The blocks of my improved silo are easily formed and may be easily laid in the wall.

20 Having thus described my invention, what I claim as new and desire to secure by Letters Patent, is:

25 1. A wall structure of the class described comprising blocks formed as rights and lefts with rabbet-like recesses at one end extending one-half the width of the blocks, said blocks being laid in tiers in coacting pairs of rights and lefts with the recesses of such pairs opposed, the length of one block of 30 each pair exceeding that of the other by the

depth of such recesses, the blocks of adjacent tiers being lapped one-half their width with the longer blocks of one tier interlocked in the recesses of the blocks of the adjacent tier, and hoops disposed over such tier joints. 35

2. A wall structure of the class described comprising blocks formed as rights and lefts with rabbet-like recesses at one end, said blocks being laid in tiers in coacting pairs of rights and lefts with the recesses of such 40 pairs opposed, one block of each pair being longer than the other, the blocks of adjacent tiers being laid with the longer blocks of one interlocked in the recesses of the other.

3. A wall structure of the class described 45 comprising blocks laid in tiers, adjacent pairs of blocks in the tiers having opposed rabbet-like recesses, one block of each pair being longer than the other, the blocks of adjacent tiers being laid with the longer blocks of one 50 interlocked in the recesses of the other, and hoops disposed over the tier joints.

In witness whereof, I have hereunto set my hand and seal in the presence of two witnesses.

JOHN S. HAINES. [L.S.]

Witnesses:

GEO. B. TISDALE,
JOHN BILDERBACK.
